UNITED STATES PATENT OFFICE.

EDWIN F. SHAW, OF BOSTON, MASSACHUSETTS.

PORTABLE GYMNASTIC APPARATUS.

SPECIFICATION forming part of Letters Patent No. 425,636, dated April 15, 1890.

Application filed November 9, 1889. Serial No. 329,788. (No model.)

To all whom it may concern:

Be it known that I, EDWIN F. SHAW, of Boston, in the county of Suffolk and State of Massachusetts, have invented certain new 5 and useful Improvements in Portable Gymnastic Apparatus, of which the following, taken in connection with the accompanying drawings, is a specification.

The object of my invention is to so construct and arrange a complete set of gymnastic apparatus that the whole may be portable, self-sustaining, and adapted to be set up in any place without any connection with or support from any source whatever. This object I attain by the mechanism shown in the accompanying drawings, in which—

Figure 1 is a view in elevation, showing the form of my apparatus with some of the gymnastic appliances attached. Fig. 2 is a view 20 in perspective, showing the principal part of the frame or standard with a number of the gymnastic appliances attached. Fig. 3 is a section in detail, showing the method of attaching the adjustable pendulum striking-ball. Figs. 4 and 5 show the construction of 25 the variable weights.

The frame of my apparatus consists of a heavy base-piece A A'. The part A' may be made detachable from the part A for convenience in packing and moving. A standard A², Figs. 1 and 2, is inserted into the part A', as shown, and has a union-coupling A³ at its top. The part of the frame marked H, Fig. 1, is connected by the said union-coupling A³ 35 to the part A².

H' is an angle-joint that connects the cross-bar H² to the upright H, and H³ is an angle-joint that serves to connect the cross-bar H² 40 to the upright H⁴, said upright H⁴ being connected to the extension part A⁶ by a coupling H⁵.

H', Fig. 1, is a multiple joint having a number of bracing-legs H⁶, attached to it.

The above-described frame is jointed together, as described, so that for packing and transportation it can be taken apart and packed in a comparatively small space.

Referring to Fig. 2, F' F' represents slide-tracks firmly attached to the base A by pins 50 f f', which may be easily withdrawn when it is desired to detach the slide-tracks. Upon the slide-tracks F' F', I have a sliding seat

F², and to the base A foot-rests F F'. B is a strong ring having radial arms or spokes B' B' B' and a hub B⁴, by which it is attached to 55 the standard A². Upon the ring B, I have swiveling traveler-blocks D and C, each of which is provided with a sheave D' C', for receiving the ropes D² and C², respectively.

For chest exercise, using both arms on the 60 same lift, I have the handles C⁵ C⁵ and the cross-bar C⁴, the bar C⁴ being attached to the rope C², to the other end of which I attach a variable weight C³, the construction of 65 which is shown in Figs. 4 and 5 and will be explained farther on. D⁵ is a handle attached to the rope D², the rope D² having a variable weight D³ attached to it. This last device is also adapted for chest exercise, and may be used alone or in connection with the 70 other chest-exercising device.

For arm exercise I have the following-described device: R is a cross-arm affixed in the standard A². Upon this arm R clamps R' R' are attached, each holding a sheave P. Around 75 each sheave a rope P' passes, the end of the rope P' being provided with handles P². This part of the apparatus is to be used by two persons pulling alternately with each hand.

For wrist exercise I attach to the end of the arm R a sleeve W, to which is attached by a pin W' a rope W², which has at its end a variable weight W³. The height of the arm R can be varied by placing it, as desired, in any one of the holes R². (See Fig. 2.) 80 85

Now, referring to Fig. 1, I will explain other parts of my apparatus. K K are flying rings attached by ropes K' K' and collars K² K² to the cross-bar H². L is an adjustable pendulum striking-ball. The ball L is made of some 90 suitable material and is attached to a rod L'. This rod L' passes through the striking-ball L, and is held in place by nuts indicated by dotted lines. The rod L' slides into a hollow rod or tube L³, and is held at the desired 95 height by means of a thumb-screw L². The rod L³ is jointed at L⁴ to the adjustable ring L⁵. (See also Fig. 3.) This ring L⁵ is held to the cross-bar H² by a set-screw L⁶ and has an arm L⁷, Fig. 3, to which is affixed a stopping-pad L⁸. This stopping-pad or check-pad is itself adjustable by its screw-stem and serves to limit the swinging motion of the 100 striking-ball L.

The variable weights referred to are all made like the one shown in Figs. 4 and 5—that is, each is made hollow, like a pail, the stem d being attached to the bottom, as shown in Fig. 4. The auxiliary weights are made as shown in Fig. 5, and are adapted to be placed within the hollow weight D^3 , as shown in Fig. 4.

For lift exercise I can remove the handle D^6 , Fig. 2, from the rope D^2 and, passing the said rope through one of the sheaves T , replace the handle, and then it is ready for the lift exercise. It is obvious that the rope C^2 C^3 may also be passed through one of the sheaves T , and thus have a double lift, or used with the sliding seat.

For trapeze exercise I have the bar V suspended by ropes V' V'' and rings V^2 V^2 to the cross-bar H^2 , Fig. 1.

20 The sliding rod M^4 , Fig. 1, is for the purpose of measuring the heights of persons, and has a graduated stem M , which slides in brackets M' M'' . M^3 is a thumb-nut, which serves to hold the rod M M^4 in place.

25 The height-measuring device is an important adjunct to my apparatus, as the adjustment of many of the other parts depends upon the height of the person using them.

Having thus fully shown and described my 30 device, what I claim as new, and desire to se-

cure by Letters Patent of the United States, is—

1. In a portable gymnastic apparatus, the combination of the base A A' , standard A^2 , and ring B with the traveling block C , having a sheave C' , the rope C^2 , variable weight C^3 , and handle device C^4 C^5 , arranged substantially as and for the purpose set forth. 35

2. In a portable gymnastic apparatus, the combination of the base A A' , standard A^2 , and cross-arm R with the clamps R' R' , each provided with sheaves, ropes or cords passing over the sheaves, and handles secured to opposite ends of said cords, arranged substantially as and for the purpose set forth. 40

3. In a portable gymnastic apparatus, the combination of the base A A' , standard A^2 , and cross-arm R with the sleeve W , eye-pin W' , rope W^2 , and variable weight W^3 , substantially as described, and for the purpose 50 set forth.

4. In a portable gymnastic apparatus, the combination of the frame, as described, having a cross-bar H^2 , with an adjustable pendulum striking-ball L , substantially as and for 55 the purpose set forth.

EDWIN F. SHAW.
